UNITED STATES PATENT OFFICE.

EDMONDO MICHELE BORGO, OF TURIN, ITALY.

PUMP WITH VARIABLE OUTPUT.

Application filed February 25, 1920. Serial No. 361,205.

To all whom it may concern:

Be it known that I, EDMONDO MICHELE BORGO, a subject of the King of Italy, residing at Turin, Italy, have invented certain new and useful Improvements in Pumps with Variable Output; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to a pump with variable output particularly applicable for the separate lubrication of the several cylinders of internal combustion engines and for like purposes.

20 This pump consists substantially of a cylindrical body working also as distributor revolving tightly in a fixed chamber and driven by the motor, or the like, at a suitable ratio of speed. This body is provided

25 with an exhaust opening which during the revolution coincides successively with several exhaust passages, having suitable check valves provided in the fixed chamber and connected at as many supply pipes for feeding

30 lubricant to the several members to be lubricated. The piston of the pump is mounted to slide, but prevented from turning inside the revolving body, and is actuated by the latter with an alternating movement, opposite to the action of a spring, by means of

35 a projection of the bottom of the revolving body, which projection engages the several teeth of a crown of teeth provided at the top of the said piston and corresponding in

40 number to that of the several members to be lubricated. Consequently, at each revolution of the body of the pump, the piston accomplishes a number of suction and compression strokes corresponding to the number

45 of the members to be lubricated. Besides, this pump is provided with a regulating device of the output by means of which it is possible to change or to annul entirely the alternating movement of the piston

50 along its axis.

A constructional form of the pump is shown by way of example in the annexed drawing in which:—The Fig. 1 shows the pump in end view, the cover having been

55 taken away;—the Fig. 2 shows the pump in longitudinal section on the line —2^x, 2^y, 2^z—

of the Fig. 1;—the Fig. 3 shows the pump in another working position in longitudinal section on the line —3^x, 3^y—of the Fig. 1;—the Fig. 4 shows in longitudinal section the body of the pump and its piston in another working position.

The pump, intended for the separate lubrication of four cylinders consists of the chamber 1, provided with the cover 2 and 65 destined to be fixed in a suitable point of the motor case 3, or the like, by means of the screws 4, which by passing through suitable holes of the cover and through the corresponding holes 5 of the chamber serve at the 70 same time for connecting the cover to the chamber 1 and the whole to the motor case 3.

The chamber 1 is provided laterally of the suction passage 6 for the lubricant whose hole 6' leads to the inside of the said chamber in correspondence with a forward cavity of the latter. The said suction passage is provided with a check valve constituted preferably by a ball 7 and spring 8, coming to rest upon the terminal sleeve 9 of the 80 feeding pipe tightly jointed to the passage 6 by means of the union nut 10. In the body of the chamber 1 there are provided all around four inclined exhaust passages 11 leading to the inside of the central cavity of 85 the chamber and enlarged in this point by means of the enlargements 11'. Each passage 11, that reaches till against the cover 2 by which it is closed, is provided with a check valve constituted by the ball 12 and 90 spring 13 and communicates above with the exhaust hole 14 closed in front by the cover 2. Each hole 14 opens to the rear in correspondence of a sleeve 15 formed in the body of the motor case and in which is fixed the 95 supply tube 16 destined for feeding the lubricant to the one of the motor cylinders. The tubes 16 which lead in a suitable point to the inside of the corresponding cylinder, are preferably arranged in the inside of the 100 motor case. Owing to this arrangement by setting up the pump on the motor case, there are also established the communications between the several exhaust passages of the pump and the corresponding feeding tubes 105 16 of the lubricant to the several cylinders. It is evident that the tubes 16 might be substituted also by suitable passages provided directly in the body of the motor case 3.

In the inside of the chamber 1 there is 110 tightly mounted and capable of rotating, the cylindric hollow body 17 of the pump driven

by the motor, or the like, under a suitable ratio of speed. The drive is obtained for instance by means of a worm 18 driven by the motor and engaged with the worm wheel 19 milled eventually in the same body 17, which is prevented from any axial movement owing to its collar 17' engaging the forward cavity of the chamber 1. The said collar 17' is provided with the groove 10 —17^a— which communicates with the internal cavity of 17 through a plurality of oblique holes —17^b—. The body 17 of the pump is provided with an exhaust hole 17" destined, during the rotation of the said body to communicate successively with the several exhaust passages 11, respectively with the enlargements 11' of these latter.

In the inside of the cylindric cavity of the body 17, bored according to two different diameters is mounted capable to slide axially the hollow piston 20 having also two different diameters of a collar 20'. In the inside of the piston 20 there are provided one or several grooves 20" (four in 25 the case of the drawing) in which engage the corresponding teeth 2" of a sleeve 2' projecting from the internal face of the cover 2. This arrangement prevents the rotation of the piston 20 but allows its axial 30 sliding. In the inside of the piston in engagement with the grooves 20" is mounted capable of sliding but prevented from turning the bushing 21 containing the spring 22 acting against the bottom of the cavity of 35 the piston. This bushing 21 with its beveled head 21' leans against the end 23' also beveled of the axis 23 mounted capable to rotate in the inside of the sleeve 2' and capable to be put in rotation from the outside 40 by means of the operating lever 24.

The bottom of the revolving body 17 of the pump is provided with the wedge shaped tooth 17''' on which engage the wedged teeth 20''' of a crown of teeth provided at 45 the end of the head of the piston 20. The teeth 20''' are in the same number as that of the suction and exhaust strokes which it is to be realized during a complete revolution of the revolving body of the pump. 50 In the case of the drawing there are four teeth.

The working is as follows:

By turning the body 17,—being for instance initially in the position of the Fig. 55 3 with its tooth 17''' in engagement with the cavities between two teeth 20''' of the piston 20,—, the said tooth 17''' by leaning on the shoulders of the teeth 20''' causes the rearward movement of the piston 20, in 60 opposition to the action of the spring 22, and after an eighth of rotation of 17 brings the piston in the position of the Figure 2.

During this rearwards movement the piston 20, through the passage 6, the groove 65 —17^a— and the holes —17^b— sucks the lu-

bricant in the interior of the cavity —a—. By continuing the rotation of the body 17 the piston 20, forced by the spring 22, return after another eighth of rotation of 17, to its initial position of the Fig. 3, whilst the teeth 20''' slide on the sides of the tooth 17'''. The piston accomplishes in this manner its compression stroke and the lubricant before sucked into —a— is delivered to that of the exhaust passages 11 with which it is then in communication through the exhaust hole 17" of the body 17.

At each revolution of the turning body 17 there are four sucking and exhausting phases and the four portions of lubricant thus sucked are separately delivered to the four cylinders to be lubricated.

The output of the pump may also be varied from a maximum till zero by varying correspondingly the piston stroke. That is obtained by moving axially the bushing 21 in such a manner that the spring 22 therein enclosed, when assuming its maximum of dilatation cannot displace axially the piston during its entire exhaust stroke. The axial movement of the bushing is realized by turning the shaft 23 by means of the operating lever 24. In this manner for instance by turning the shaft 23 for 180° from the position of the Fig. 2, its beveled edge 23' is brought in the position of the Fig. 4 and allows consequently the maximum rearwards movement of the bushing 21, whose beveled edge 21' leans on that 23' of 23. Then the spring 22 even if resuming its maximum of dilatation cannot push forward the piston 20 so that the teeth 20''' might engage with the wedge 17'''; thereby the piston remains immovable and the output of the pump is equal to zero. At each intermediate rotation of the shaft 23, comprised in the said maximal rotation of 180° correspond an intermediate output of the pump which may in this manner be regulated by insensible degrees by moving the lever 24 100 for an angular amplitude of 180°.

In the example above described it is assumed that the pump is capable to furnish at each revolution of the body 17, four distinct portions of lubricant, but it is evident that this number may vary more or less by varying the number of the teeth 20''' of the head of the piston and consequently that of the exhaust passages. Moreover, it is assumed that the pump is destined to the separated lubrication of the several cylinders of an internal combustion motor, but it is evident that it may serve for many other applications generally for the separated lubrication of the several members of whatever engine.

I claim:

1. A pump comprising a casing having an inlet and discharge port, a cylinder fitted to rotate in said casing and having inlet and 130

discharge ports periodically brought into communication with said casing ports respectively, a piston in said cylinder, a cam in the cylinder and a cam on the piston co-5 operating therewith, and a spring in said cylinder to urge said cams into contact.

2. A pump comprising a stationary casing, having an inlet port and a plurality of outlet ports, a cylinder fitted in said casing 10 having an inlet port and a plurality of discharge ports, the latter ports periodically brought into communication with said outlet ports during the rotation of the cylinder, a spring-urged piston in said cylinder 15 and co-acting cams in said cylinder and on said piston to reciprocate the latter.

3. A pump comprising a cylindrical casing having a discharge port, a cylinder rotatable in said casing and having a distributing port and a liquid inlet, a spring urged piston reciprocable in said cylinder, means 20 on the piston and means in the cylinder co-operating with said piston means to reciprocate the piston when the cylinder is rotated.

4. A pump comprising a cylindrical casing having a discharge port, a cylinder rotatable in said casing and having a distributing port and a liquid inlet, a spring urged piston reciprocable in said cylinder means 30 on the piston and means in the cylinder co-operating with said piston means to reciprocate the piston when the cylinder is rotated and means to vary the spring pressure 35 on the piston.

5. A pump comprising a cylindrical casing having a plurality of discharge ports, a cylinder rotatable in said casing and having a distributing port capable of successively 40 registering with the discharge ports, said cylinder also having a liquid inlet, a spring urged piston slideable in but not rotatable

with said cylinder and controlling said liquid inlet, and cams on the end of the piston and in the end of the cylinder to reciprocate the piston against its spring pressure, and means to vary the spring pressure. 45

6. A pump comprising a cylindrical casing having discharge ports, a cylinder mounted therein having a liquid inlet and 50 a distributing port, a piston in the cylinder, a spring in the piston to urge it in one direction, means in the cylinder to urge the piston in the opposite direction when said cylinder is rotated, means on said cover to 55 prevent the rotation of the piston and bolts fastening said cover on said casing simultaneously acting as means to secure the casing to its support.

7. A pump comprising a casing having a 60 liquid supply and a plurality of discharge ports from a central bore, said ports having peripheral extensions at said bore, a rotatable cylinder controlling said ports and having a flange at one end seated in said casing 65 and having a plurality of liquid inlets and a distributing port, said flange having a peripheral groove connecting said inlets and registering with said supply, a piston in said cylinder controlling the inlets, a cover holding the parts in assembled position, means on the cover to prevent rotation of the cylinder, a spring holder in the piston having a cam face, a spring between said holder and one end of the piston, means mounted on 70 the cover to co-operate with said cam to adjust the position of said holder and the tension of its spring, a cam in the cylinder and a plurality of cams on the end of the piston co-operating with the cylinder cam. 75

In testimony that I claim the foregoing as my invention, I have signed my name. 80

EDMONDO MICHELE BORGO.
